UNITED STATES PATENT OFFICE

EDMUND ECKART, OF NEW ROCHELLE, NEW YORK.

CAN-CLOSURE.

No. 868,850.

Specification of Letters Patent.

Patented Oct. 22, 1907.

Application filed January 18, 1906. Serial No. 296,600.

To all whom it may concern:

Be it known that I, EDMUND ECKART, a citizen of the United States, and a resident of New Rochelle, Westchester county, State of New York, (whose post-office address is 231 East Forty-second street, borough of Manhattan, New York city, New York,) have invented certain new and useful Improvements in Can-Closures, of which the following is a specification.

My invention relates to means for closing cans or receptacles for liquids, or solids in powdered form, in such a manner that the said cans or receptacles shall be closed air-tight and water tight, and may at the same time be opened without the use of a cutting tool.

The invention is illustrated in the accompanying drawings in which

Figure 1 is a plan view, partially broken away, and Fig. 2 a partial sectional elevation of a closed can embodying my invention; Fig. 3 is a detailed sectional view showing in exaggeration the positions of the spring part of the cover when removed and when in place on the body of the can.

Referring to the drawings, A represents a sheet metal can provided with a top portion B suitably secured thereto. As shown in this instance the inner edge portion of the part B is bent, first downward, and then upwardly, so as to form a groove C, and is then bent inwardly at D and downwardly, so as to provide a frictional contact portion E.

The sheet metal cap F is provided with a wall G, an outwardly bent portion H, a backward turn or bend I and a downwardly extending spring portion K.

In Fig. 2 the can is shown closed, with the cap in place. It will be seen that the cap is frictionally held by the contact of its wall G with the part E of the can, and of its spring piece K with the inner wall of the groove C on the can. The position of the spring portion K is indicated in dotted lines in Fig. 3. The relation between the positions respectively assumed by

the part K is shown in an exaggerated manner for the sake of clearness.

It will be noted that the lower edge of the portion K is not beaded or upturned as in many cans now on the market, the necessary point of application for the lever used in opening the can being located at the upper edge, thus leaving the entire portion K sprung.

When the parts are properly constructed, the can, when closed, will be watertight and airtight. The cap may be removed by prying it up by means of a coin, in the usual manner, the coin being fulcrumed on the outer edge of the can, and bearing upon the lower portion of the bend I.

The structure of my can-closure may be varied in many details without departing from the spirit of my invention as expressed in my claims.

Therefore, without limiting myself to the construction shown and described or enumerating equivalents, I claim

1. A can closure comprising a lid, a cross-section of the edge of which is shaped like an inverted U, at the outer arm of which is located a springy flange, the said U-shaped part being adapted to fit over an annular rim on the top of the can having a similar cross-section, producing thus a double annular seal with the edge only of the outer springy flange of the lid fitting against a rigid flange of the rim on the top of the can, substantially as described.

2. A can closure comprising a lid a cross-section of the edge of which is shaped like an inverted U, at the outer arm of which is located a springy flange, the said U-shaped part being adapted to fit over a similar annular rim on the top of the can so that the edge only of the springy flange of the can fits against a rigid flange on the can and the rigid flange of the cover fits against the innermost free flange of the can, substantially as described.

In testimony whereof I have signed my name to this specification in the presence of two subscribing witnesses:

EDMUND ECKART.
